UNITED STATES PATENT OFFICE
CERTIFICATE OF CORRECTION

Patent No. Des. 243,073 Dated Jan. 18, 1977

Inventor(s) Jack H. Kulp and James M. Florsheim

It is certified that error appears in the above-identified patent and that said Letters Patent are hereby corrected as shown below:

On the Title Page, column 2, line 19 should read.

--The drum is stippled to indicate contrast.
The warning lights are shown in broken lines in
Figs. 1, 2, 3 and 4 for illustrative purposes only.--

Signed and Sealed this
Twelfth Day of April 1977

[SEAL]
